UNITED STATES PATENT OFFICE.

WILFRED ROTHERY WOOD, OF LONDON, ENGLAND.

MECHANICAL STOKER.

1,087,155.

Specification of Letters Patent. Patented Feb. 17, 1914.

Application filed April 28, 1913. Serial No. 764,131.

To all whom it may concern:

Be it known that I, WILFRED ROTHERY Wood, a citizen of the United States of America, residing at London, England, have 5 invented new and useful Improvements in Connection with Mechanical Stokers, of which the following is a specification.

This invention relates to that class of mechanical stokers in which the fuel is received 10 on the grate at one side or end, and the refuse is discharged at the opposite side or end. Included in this class is what are known as the traveling grate or chain grate stokers. In this class of stoker difficulty is 15 sometimes experienced in securing complete combustion of the fuel before it reaches the end of the grate where the discharge takes place.

Dams, bars, or chains, some of which have 20 been fixed and others movable with relation to the grate, are sometimes used near the discharge end to obstruct the travel of the fuel so as to give more time for its complete combustion, but even with the movable class 25 it has not been customary to remove the dam or bars away from the intense heat of the fire, and such dams or bars being constantly exposed to high temperatures are apt to burn away; and the further objection to 30 their use is that with some fuels they cause the accumulation of clinkers to such an extent as to destroy the full burning effectiveness of the grate. According to this invention not only are these difficulties overcome, 35 but a greater agitation of fuel at the discharge side of the grate, and hence more complete combustion is secured. These results are obtained by giving the bar or dam a to and fro movement—toward and away 40 from the advancing fuel. In the forward movement it presses forward at the back end of the grate both the unburned fuel and refuse. The return movement is such as to remove the bar from the intense heat of the 45 fire, and to such a position as to permit of the refuse, accumulated by the previous movement, to be discharged either over or under the bar into the ash pit. Many mechanical movements may be employed to 50 give the desired to and fro motion of the bar.

In the accompanying drawings the invention is illustrated as being applied to a traveling or chain grate stoker, and in same 55 Figure 1 is a side elevation partly in section;

when the dam is withdrawn from the grate; Fig. 3 a rear end elevation; Fig. 4 a plan view of same; Fig. 5 shows one of the numerous other forms which may be employed for moving the dam to and fro; and Fig. 6 is a plan view of same.

In the drawings only so much of mechanism and furnace are shown as will enable the invention to be clearly followed.

Referring first to Figs. 1 to 4 it will be 65 noted that mounted at the rear of the stoker and on either side of same are arms 1 pivoted at 2 in bracket 3 through which passes in this case the driven shaft 4 of the stoker. On the outer end of shaft 4 is a plate 5 70 carrying rollers 6 adapted as shaft 4 is revolved to make contact with the inclined surfaces 7 carried by arms 1. It will be seen that the rollers 6 and the inclined surfaces 7 form a species of cam which in turn im- 75 parts motion to the arm 1.

The dam is shown as consisting of a number of sections 8 carried by arms 9 that terminate at their outer ends in open sleeves 10 which when arms 9 are held in a vertical position enable the sleeves to be slipped over the oval bar 11 and the bar 9 to be turned down so that its outer end can rest on the grate. The outer ends of the oval bar 11 are squared so as to be adapted to be held in either of the recesses 12 at the top of arms 1 so that the point on the grate to which the dam 8 is to travel may be varied as desired. 80

The action of the parts heretofore described is as follows: As the driven shaft 4 90 revolves the rollers 6 alternately make contact with the inclined surfaces 7 and the arm 1 is rocked or caused to reciprocate so as to alternately travel onto the grate and push or bank up the ashes and clinker thereon and then to at once retire from the fire zone to a point say as indicated by dotted lines in Fig. 1 thus removing the outer ends 8 of the bars 9 from the intense burning action of 95 the fire.

In Figs. 5 and 6 the dams 8 are mounted on a cranked shaft 13 carried through the wall of the furnace and capable of being rotated by any suitable means while a cross shaft or support 14 may be employed to prevent the dam from falling downwardly when in its retracted position. The action of the dam 8 is exactly the same as that illustrated in the previous figures in that it advances over the rear end of the grate 110

banks up the ashes and clinker and retires out of the fire zone.

It is obvious that numerous arrangements other than those illustrated can be designed 5 which will effect the to and fro motion of the dam and that the invention may be applied to other classes of stokers than those in part illustrated and that the dam may be a continuous rigid bar or a flexible one so 10 long as it is adapted to push or bank up the traveling fuel or ash and then retire from the zone of intense heat and permit the refuse or eventual ash to be discharged.

What I claim is:—

- 15 1. In mechanical stokers and in combination a movable grate, a dam for banking up the fuel at the discharge end thereof, means operated by the driving mechanism for advancing said dam toward the advancing fuel 20 and means operated by the driving mechanism for withdrawing said dam to a position free from the intense heat of the fire.
- 25 2. In mechanical stokers and in combination, a movable grate, a dam for banking up the fuel at the discharge end thereof, means operated by the movable grate for advancing said dam toward the advancing fuel and means operated by the movable grate for

30 withdrawing said dam to a position free from the intense heat of the fire.

3. In mechanical stokers and in combination, a movable grate, a dam for banking up the fuel at the discharge end thereof, a revolving grate-operating shaft, pivoted arms carrying the dam, and a member on said 35 grate operating shaft for causing said pivoted arms to rock and carry the dam toward the advancing fuel and also to withdraw said dam to a position free from the intense heat of the fire.

4. In mechanical stokers and in combination, a movable grate, a dam for banking up the fuel at the discharge end thereof, a revolving grate-operating shaft, pivoted arms carrying the dam, cam surfaces on the arms 45 and a cam member on the said shaft adapted to coöperate with the inclined surfaces to rock the pivoted arms.

In witness whereof I have hereunto set my hand in the presence of two subscribing witnesses.

WILFRED ROTHERY WOOD.
